UNITED STATES PATENT OFFICE

THOMAS LLOYD SAMPSELL, OF CAMBRIDGE, MASSACHUSETTS

STARTING DEVICE

Application filed March 11, 1932. Serial No. 598,243.

This invention relates to starting devices for horse races, and more particularly to the type which are adapted to restrain the horses at the starting line and to be readily and quickly released at the instant the race is intended to begin.

The general object of the invention is to provide a novel and improved form of horse race starting device.

10 A more particular object is to provide a device of this character which includes means adapted to be operated by each jockey to release his mount upon the giving of a predetermined signal announcing the start of 15 the race.

In its preferred embodiment, the invention contemplates the provision of semi-flexible means, such as cables, wrapped chains, or the like, associated with the horses' bridles, 20 whereby they may be connected to each other and to starting posts on either side of the track, and individual means for separately detaching the semi-flexible means from the bridles at the start of the race.

25 Other objects and features of novelty will be apparent to one skilled in the art upon a consideration of the following specification when read in connection with the accompanying drawing, in which certain embodiments 30 of the invention are illustrated by way of example.

In the drawing:

Figure 1 is a fragmentary view in perspective of the starting line of a race track, 35 illustrating the application of the invention;

Figure 2 is a view in front elevation of a portion of a bridle to which my improved starting device has been applied, a portion of one of the bit rings being shown in cross 40 section;

Figure 3 is a detailed perspective view illustrating the manner by which the device is released at the start of a race; and

45 Figure 4 is a detailed view showing a modification of my improved starting device.

In Figure 1 of the drawing, several horses are shown lined up in order between the starting posts 10 and 11 disposed on either side of the track. Instead of the usual complicated barrier structure employed in start-

ing races of this type, the present invention contemplates the provision of a simple means for connecting the bridles 12 of the contesting horses to each other at points near the bits, or directly at the ends of the bits, and also means for connecting the outside and inside horses to the posts 10 and 11. The bridles 12 are of the usual simple type generally applied to race horses and are seen to comprise the cheek pieces 13, the nose band 14, the fronts 15, the throat latches 16, the bits 17 (together with their rings 18), and the snaffle reins 20. In the illustrated embodiment, each of the bit rings 18 is provided with small links 21 which are provided with two eyes, one of which is adapted to receive the ring 18 and the other, numbered 30, to provide means for detachably connecting the lengths of semi-flexible material 22 by which the bridles of adjacent horses are adapted to be connected.

The connecting members 22 may be of any suitable semi-flexible material such as cable or, as illustrated in the present disclosure, may be composed of chains 23 wrapped in leather or any suitable fabric such as canvas or the like, as shown at 24. The connecting members 22 which are used to secure the inside horses to the inner post 11, and also those which are employed to connect adjacent horses, may be approximately two and one-half feet in length, and since the number of entries in a race is seldom enough to form a line extending entirely across the track, the outside connecting member 25 may be of any necessary length to extend from the outside horse to the post 10. Any suitable type of detachable connection 26 may be employed to secure these end members to the posts.

Each end of each of the connecting members 22 is provided with means such as, for example, the bifurcated member 28, the arms of which are perforated as at 29 and are adapted to receive between them the link 21 attached to the bit ring 18. The holes 29 of the member 28 and the perforation 30 of the link 21 are adapted to register when they are connected, and a suitable pin member 31 is adapted to pass therethrough, as clearly

shown in Figure 2 of the drawing. This connection is, of course, duplicated on the opposite side of the horse's head, and the two pins 31 are connected by means of the light cord or line 32 which provides a sort of supplemental or auxiliary rein by which the jockey may withdraw the pins 31 and thus quickly release the connecting and restraining elements 22. When these elements are released at the start of a race, they drop down upon the track and remain there until they are gathered up for use in a subsequent contest. These members 22 provide no obstacle to the progress of the horses since, due to their semi-flexible nature, they are not likely to be wrapped around the horses' legs but will be merely kicked aside if they happen to fall in front of the animal. The releasing rein 32 together with the pins 31 may, of course, be discarded by the jockey when the race has begun, or means, not shown, may be provided for retaining the releasing apparatus on the horse during the race.

It will be readily understood that the detachable connection between the horses' bridles and the connecting members 22 may be varied in any manner within the scope of the present invention and may comprise, if desired, any type of quick detachable snap connection which may be applied to an ordinary type of bit ring without modification thereof.

In a modified form of the device, illustrated in Figure 4 of the drawing, the bit member 17' is provided at each of its ends near the point where they are connected to the bit rings 18', with the projections or lugs 21' which corresponds in function to the members 21 of the previously described embodiment and which are provided with the perforations 30' through which the releasing pin is adapted to extend. In this embodiment, any tension in the aligned restraining elements will be transmitted directly from one adjacent bit to the other and will thus eliminate distortion of the bit arrangements which might possibly occur if the connections were made at other points around the bit rings.

The advantages of the present invention will be readily apparent. The securing of the horses to each other and to the starting posts at properly spaced intervals affords a means for preventing high-strung and nervous animals from rearing, prancing, or otherwise interfering with each other, as is very frequently the case when it is endeavored to line them up before an ordinary barrier at the start of the race. The present device insures an even start or, at any rate, puts the burden of making a quick getaway upon the individual jockey, whose duty it is, upon the giving of the starting signal, to release his own mount.

It will be readily understood that various changes and modifications may be made in the embodiments illustrated and described herein without departing from the scope of the present invention as defined by the following claims.

Having thus described the invention, what is claimed as new and desired to be secured by Letters Patent is:—

1. In a starting device for horse races, in combination, restraining means for said horses and individual means associated with each horse operated by the jockey for releasing said restraining means.

2. In a starting device for horse races or the like, in combination, restraining means for the horses and individual means associated with the harness of each horse operated by the jockey for releasing said restraining means from said horse.

3. In a starting device for horse races or the like, in combination, restraining means directly connecting adjacent horses and a separate means associated with each horse and under the control of the jockey for releasing said restraining means.

4. In a starting device for horse races or the like, in combination, a starting post, restraining means directly connecting adjacent horses and the end one to said post, and a separate means associated with each horse for releasing said horse from the next adjacent one and from said starting post.

5. In a starting device for horse races or the like, in combination, a series of members adapted to connect the bridles of adjacent horses, and separate means associated with each bridle under the control of the jockey for releasing said connecting members.

6. In a starting device for horse races or the like, in combination, a pair of starting posts, restraining means comprising a series of semi-flexible members, some of them adapted to connect the bridles of adjacent horses together and the others adapted to connect the bridles of the end horses of the starting line with said posts, and releasing means comprising a supplemental rein associated with each bridle and adapted to effect quick attachment of said members from said bridles when actuated by the jockey.

7. In a starting device for horse races or the like, in combination, a starting post on each side of the track, restraining means for the horses comprising a series of semi-flexible elements, the end ones of said elements adapted to be connected with said posts, quick detachable connecting means for securing said elements to the bit rings of the bridles and a supplemental rein associated with said quick detachable means, whereby each jockey may release his mount from said restraining means upon the giving of the signal for the start of the race.

8. In a starting device for horse races or

the like, in combination, a starting post on each side of the track, restraining means for the horses comprising a series of semi-flexible elements, the end ones of said elements adapted to be connected with said posts, quick detachable connecting means for securing said elements to the ends of the bits, and a supplemental rein associated with said quick detachable means, whereby each jockey may release his mount from said restraining means upon the giving of the signal for the start of the race.

In testimony whereof I hereunto affix my signature.

15 THOMAS LLOYD SAMPSELL.
